United States Patent Office

Des. 226,833
Patented May 8, 1973

226,833

CONCRETE RAFTER SUPPORT

Marvin L. Rich, 1018 Opal, Boise, Idaho 83705

Filed Apr. 9, 1971, Ser. No. 132,926

Term of patent 14 years

Int. Cl. D8—08

U.S. Cl. D8—235

FIG. 1 is a right front perspective view of the concrete rafter support embodying my new design.

FIG. 2 is a left rear perspective view as viewed from the bottom.

I claim:

The ornamental design for a concrete rafter support, substantially as shown.
